UNITED STATES PATENT OFFICE

DANIEL F. SULLIVAN, OF LOWELL, MASSACHUSETTS, ASSIGNOR OF ONE-HALF TO JOHN P. FUREY, OF LOWELL, MASSACHUSETTS

STOP MOTION FOR KNITTING MACHINES

Application filed July 13, 1929. Serial No. 377,999.

This invention relates to a stop motion for knitting machines and has for its general object to provide a stop motion which is simple in construction, which can be easily and inexpensively made and which will be effective in operation.

In order to give an understanding of the invention I have illustrated in the drawings a selected embodiment thereof which will now be described after which the novel features will be pointed out in the appended claims.

Fig. 1 is a front view of the stop motion with parts broken out;

15 Fig. 2 is a section on the line 2—2 showing the parts in normal operating position;

Fig. 3 is an enlarged fragmentary sectional view on substantially the line 2—2 but illustrating the manner in which the stop motion 20 operates when the yarn breaks or becomes unduly slack;

Fig. 4 is a view illustrating a thread-releasing device which releases the thread thereby permitting the stop motion to act 25 whenever the thread becomes unduly taut.

Inasmuch as my present invention relates simply to the stop motion I have not thought it necessary to illustrate the knitting machine but have confined the drawings to the stop 30 motion features.

In the drawings 1 indicates part of the frame of a knitting machine on which is supported one or more bobbins 2. The yarn is drawn off from the bobbin 2 in an upward vertical direction and after passing through 35 a guide secured to the frame above the bobbin the yarn passes down to the knitting point, this being the usual construction. My improved stop motion is arranged to act on the yarn between the bobbin and the upper guide and is arranged so that if the yarn breaks or becomes unduly slack the knitting machine 40 will be stopped.

The improved stop motion is also constructed so that if the yarn as it comes from the bobbin contains a knot or bunch the knitting machine will be stopped before the knot, bunch or imperfect section of yarn reaches the knitting point.

50 The mechanism for controlling the knit-

ting machine is not shown herein as it may be any mechanism usually employed for starting and stopping knitting machines and such mechanism is controlled by a link 3 which is connected to an arm 4 fast on a rock shaft 5 that is journalled in bearings 6 formed in the upright 7 of a suitable frame that is supported on the table 1. The construction is such that when the rock shaft 5 is turned clockwise Fig. 2 the resultant movement which is given to the link 3 will serve to stop the knitting machine either by releasing the shipper rod or by throwing out the clutch or in any other way commonly employed in knitting machines. For the present purposes it is not necessary to illustrate any stopping mechanism as it will be understood that the rocking of the shaft 5 serves to effect the stopping of the knitting machine in usual way.

The rock shaft 5 has fast thereto an 55 upright arm 8 which is provided in one edge near its upper end with a through-and-through slot 9. Pivoted to the arm 8 is a drop member 10, said drop member having a laterally-extending portion 11 which is normally in alignment with the slot 9. The thread 12 from the bobbin 2 extends through a guide eye 13 carried by the lower end of the arm 8 and extends along the surface of said arm and across the slot 9 as seen in Fig. 2. Normally the laterally-extending portion 11 of the drop member 10 overlies the thread, the thread passing between said portion 11 and the face of the arm 8. While the machine is running, therefore, the drop member 10 will be supported by the thread and will be held in the position shown in Figs. 1 and 2. If the thread 12 breaks or becomes unduly slack it ceases to support the drop member 10 and the latter falls through the slot 9 60 and swings backwardly into the position shown in Fig. 3.

Means are provided to engage the drop member 10 when it gravitates into the position shown in Fig. 3 and thereby to swing the 65 arm 8 forwardly thus causing a turning movement of the rock shaft 5 which will be sufficient to stop the knitting machine. The means for accomplishing this is in the form of a toothed wheel 14 which is fast on a con- 70

tinuously-rotating shaft 15 mounted in bearings 16 formed on the supporting arms 7. This shaft 15 is shown as being provided with a driving pulley 17 by which it may be continuously rotated.

The normal position of the shaft 5 and arm 8 during the running of the knitting machine is shown in full lines in Fig. 2 and so long as the thread is intact and is under the proper tension the drop member 10 will be held in its inoperative position shown in full lines Fig. 2 by its engagement with the yarn. When in this position it is out of the path of movement of the teeth of the wheel 14 so that said wheel is permitted to rotate freely.

When the yarn 12 breaks, however, the drop member 10 will be no longer supported by the yarn and will gravitate into the dotted line position Fig. 2, in which position the laterally-extending portion 11 of the drop member is in the path of movement of the teeth 18 of the toothed wheel 14. The stop member will thus be engaged by one of the teeth and as the wheel continues to rotate the stop member will be forced to the right Fig. 2 and will thereby swing the arm 8 from the position shown in Fig. 2 to that shown in Fig. 3. This swinging movement of the arm gives the rock shaft 5 a sufficient turning movement to effect the stopping of the knitting machine.

The same operation will result if the yarn becomes unduly slack. For if the yarn is sufficiently slack the member 10 will gravitate into the dotted line position Fig. 10 thereby bringing it into position to be engaged by the teeth 18 of the toothed wheel 14.

The invention also provides means whereby the drop wire 10 will be released and thus co-operate with the toothed wheel 14 to stop the machine if the yarn contains a bunch or a knot. Pivoted to the arm 8 at 27 is a swinging knot catcher 26 which is provided with a forked end 28 through which the yarn passes. The slot in this forked end is wide enough to receive the perfect yarn but if the yarn contains a knot so large that it will not pass through the slot the engagement of the knot with the knot catcher 26 will swing it upwardly into the dotted line position. It will be noted that the knot catcher normally occupies a downwardly-inclined position resting on a stop pin 31. The upward swinging movement of the knot catcher into the dotted line position causes the yarn 12 to be moved laterally as shown by dotted lines Fig. 1 and this lateral movement is sufficient to carry the yarn out from under the free end of the laterally-extending portion 11 of the drop wire, thus freeing the drop wire to allow it to fall into the dotted line position Fig. 2 and thereby co-operate with the toothed wheel 14 to stop the knitting machine. This stopping of the knitting machine occurs before the knot has time to reach the knitting point.

My invention also provides means whereby if the yarn becomes unduly taut it will cause the operation of the stop device before the yarn breaks.

To accomplish this I have provided the device illustrated in Fig. 4 and which forms a support over which the yarn passes after it leaves the arm 8 and before it is led to the knitting point.

30 indicates a bracket which may be secured in any suitable way to the frame of the knitting machine above the parts shown in Figs. 1, 2 and 3. Pivoted at 31 to the bracket is a yarn-supporting arm 32 over which the yarn 12 passes. This arm is acted on by a spring 33 which normally holds the arm in the operative position shown in Fig. 4, a stop 34 being provided to limit the spring-imelled movement of the arm. The free end of the arm 32 operates in a guard loop 35 that is secured to the bracket 34, this guard permitting free swinging movement of the arm but normally holding the yarn 12 from running off the arm.

So long as the tension on the yarn is normal the yarn-supporting arm 32 will be retained in its operative horizontal position shown in full lines Fig. 4. If, however, the yarn becomes unduly taut, as might be the case if there was a knot in the yarn which caught on some object, then the strain on the yarn will overcome the spring 33 and will cause the yarn-retaining arm 32 to swing downwardly into the dotted line position Fig. 4. When the yarn-retaining arm reaches this position the yarn 12 will slip off from the end of the arm thereby producing in the yarn the necessary slackness which will allow the stop mechanism to work as above described.

When the machine is manually stopped for any reason and no yarn is being drawn from the bobbin 2, there might be a tendency for the weight of the drop wire 10 to pull off sufficient slack from the yarn 2 to permit the drop wire to swing into the dotted line position Fig. 2, in which case when the machine was started up again the stop motion would automatically operate. In order to prevent this I have provided the swinging clamping member 22 pivoted to the arm at 23 and provided with the clamping portion 24 that overlies the yarn 12. So long as the machine is in operation this clamping member 24 is held in inoperative position by a cam projection 25 rigid with the drop wire 10. When the drop wire is in the full line position shown in Fig. 2 the cam projection 25 engages the clamping member 22 and holds the portion 24 out of engagement with the arm 8 but when the drop wire 10 swings backwardly slightly this projection 25 is withdrawn from the clamping member 22 and the latter gravitates into its operative position shown in Fig. 3. In this position the finger or portion 24 thereof engages the yarn and clamps it against the arm

8 thereby applying sufficient tension to the yarn to prevent it from being pulled off from the bobbin by the weight of the drop wire 10. The member 24, therefore, serves to prevent the stop motion from acting when the machine is manually brought to rest.

The rock shaft and arm 8 are shown as normally held in the position shown in Figs. 1 and 2 through the medium of a spring 19 which encircles the shaft 5 and one end of which is connected to a bearing 6 and the other end of which is connected to a collar 20 that is fast on the shaft. The spring is arranged to resist the turning movement of the rock shaft 5 from the position shown in Fig. 2 to that shown in Fig. 3 and said shaft will be held in the position shown in Figs. 1 and 2 by the engagement of the arm 4 with a stop pin 21.

20 I claim.

1. In a stop motion for knitting machines, the combination with a rock shaft adapted by its turning movement to operate a stopping mechanism, a slotted arm fast on the rock shaft, the yarn leading to the knitting point passing across said slot, a drop member pivoted to the arm and normally supported by the portion of the yarn spanning the slot, whereby when the yarn breaks or becomes unduly slack the drop member will gravitate through the slot into abnormal position, a constantly-rotating toothed wheel, the teeth of which move in a path traversed by the drop member when it gravitates into abnormal position, whereby engagement of the teeth with the drop member will swing the arm forwardly and turn the rock shaft thereby to operate the stopping mechanism, and means to apply a clamping action to the thread between the drop member and the source of supply when said drop member begins to gravitate into abnormal position.

2. In a stop motion for knitting machines, the combination with a rock shaft adapted by its turning movement to operate a stopping mechanism, an arm fast on the rock shaft, a drop member pivoted to the arm and normally held in elevated position by engagement with the yarn, said stop member gravitating into abnormal position when the yarn breaks or becomes unduly slack, a constantly-rotating toothed wheel, the teeth of which move in a path traversed by the drop member when it gravitates into abnormal position, whereby the engagement of the teeth with the drop member will turn the rock shaft to cause the stop mechanism to operate, and a retaining member normally held in inoperative position by the drop member when the latter is in normal position, said retaining member gravitating into operative position to clamp the yarn against the arm when the drop member starts to gravitate into its abnormal position.

3. In a stop motion for knitting machines,

the combination with a rock shaft adapted by its turning movement to operate a stopping mechanism, of an arm fast on the rock shaft, a drop member pivoted to the arm and held in elevated position by a normally-tensioned yarn, a constantly-rotating toothed wheel, said drop member when released from the yarn gravitating into abnormal position into the path of movement of the teeth of said toothed wheel, a yarn-clamping member normally held out of engagement with the yarn by the drop member when the latter is in normal position, said clamping member gravitating into clamping engagement with the yarn during the initial gravitating movement of the drop member.

4. In a stop motion for knitting machines, the combination with a rock shaft adapted by its turning movement to operate a stopping mechanism, an arm fast on the rock shaft, a drop member pivoted to the arm and normally held in elevated position by engagement with the yarn, said stop member gravitating into abnormal position when the yarn breaks or becomes unduly slack, a constantly-rotating toothed wheel, the teeth of which move in a path traversed by the drop member when it gravitates into abnormal position, whereby the engagement of the teeth with the drop member will turn the rock shaft to cause the stop mechanism to operate, a thread-clamping element adapted to apply clamping pressure to the thread between the source of supply and the drop member, and means associated with said drop member to maintain the thread-clamping element in inoperative position while the drop member is in normal position and to allow the clamping member to become operative when the drop member moves into an abnormal position.

5. In a stop motion for knitting machines, the combination with a rock shaft adapted by its turning movement to operate a stopping mechanism, an arm fast on the rock shaft, a drop member pivoted to the arm and normally held in elevated position by engagement with the yarn, said stop member gravitating into abnormal position when the yarn breaks or becomes unduly slack, a constantly-rotating toothed wheel, the teeth of which move in a path traversed by the drop member when it gravitates into abnormal position, whereby the engagement of the teeth with the drop member will turn the rock shaft to cause the stop mechanism to operate, and means to apply a clamping action to the thread between the drop member and the source of supply when said drop member begins to gravitate into abnormal position.

In testimony whereof, I have signed my name to this specification.

DANIEL F. SULLIVAN.
